UNITED STATES PATENT OFFICE.

CONRAD DRESSLER, OF CLEVELAND, OHIO, ASSIGNOR TO AMERICAN DRESSLER TUNNEL KILNS, INC., OF NEW YORK, N. Y., A CORPORATION OF NEW YORK.

METHOD OF AND APPARATUS FOR BLUING PORCELAIN.

Application filed May 17, 1920, Serial No. 382,004. Renewed July 17, 1923.

To all whom it may concern:

Be it known that I, CONRAD DRESSLER, a subject of the King of Great Britain, and resident of Cleveland, in the county of 5 Cuyahoga and State of Ohio, have invented certain new and useful Improvements in Methods of and Apparatus for Bluing Porcelain, of which the following is a specification.

10 The general object of the present invention is to provide for the efficient bluing of porcelain in a continuous tunnel kiln.

In bluing porcelain it is necessary, in order to effect certain desired chemical reactions and physical changes in the porcelain, to subject the latter to different atmospheres in different stages of the firing operation.

In the ordinary process of bluing porcelain in an intermittent kiln, the porcelain packed 20 in wadded saggers, is subjected in an initial stage of the firing operation to a reducing atmosphere, mainly, I believe, because it is practically difficult to have any other kind of an atmosphere in the kiln when the 25 fire in the latter is being started. After a short initial period, the atmosphere in the kiln is given an oxidizing character by supplying air at a rate greater than that required for the complete combustion of the 30 fuel being burned, and this oxidizing atmosphere is maintained throughout the major portion of the heating up stage, partly because it is necessary to get rid of the smoke which has penetrated the saggers in the initial firing with a reducing atmosphere, and 35 partly because all carbonaceous matter must be burned out of the porcelain in order to produce a product which is white to the core. When the porcelain approaches its 40 final temperature and before the felspathic glaze commences to vitrify, a reducing atmosphere is maintained in the kiln for a short period in order to reduce the small amount of iron at the surface of the ware 45 from red iron oxide to the black ferrous-ferric oxide and thereby give the porcelain the desired bluish tinge. Finally the ware is subjected again to an oxidizing temperature at the stage in which the glaze begins to 50 flow. This final oxidizing stage is desirable in order to obtain a smooth glaze, and is ordinarily necessary also in order to prevent variations from desired coloring in the decoration of the ware, especially when the 55 decorative coloring is due to metallic ingredi-

ents in the glaze which should exist in the finished ware in the form of metallic oxides and not in the metallic form. In the actual practice of bluing porcelain in an intermittent kiln, it is common to divide the reducing stage preceding the final oxidizing stage into two reducing periods with an intervening oxidizing period. This sub-division is due mainly or wholly, I believe, to the difficulty of insuring penetration of the reducing atmosphere to the ware enclosed in the saggers without overdoing the reducing effect, in other words it is done because experience has taught that it is safer to impart the reducing effect in two small impulses with an intervening oxidizing effect than by a single strong reducing impulse.

One object of the present invention is to provide for the subjection of the ware as it passes gradually through a continuous tunnel kiln to conditions closely approximating those which have been found to give satisfactory results when the ware is fired in an intermittent kiln. I believe, however, that with the better control of the kiln atmosphere and temperatures attainable with the present invention, and in view of the fact that with it, it is unnecessary to pack the porcelain in tightly closed saggers, a single reducing atmosphere stage intervening between the primary and secondary oxidizing atmosphere stages will be sufficient. With my present invention I regard it as wholly unnecessary to employ the initial reducing atmosphere stage.

In carrying out my invention I employ a continuous tunnel kiln of the muffle heated type and preferably a kiln of the well known Dressler type in which the kiln chamber is heated by internal combustion 95 chambers and the transfer of heat from the internal combustion chamber to the ware is primarily by means of convection currents of the kiln atmosphere. With a kiln of this character it is comparatively simple to 100 maintain a very precise control of the temperature conditions in different zones or sections of the kiln chamber, and it is also readily possible with the special provisions hereinafter illustrated and described to maintain 105 determined atmospheres definite in character and differing from one another in successive zones or sections of the kiln chamber.

The various features of novelty which 110

characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred form of apparatus and method of operation devised by me.

Of the drawings:

Fig. 1 is a somewhat diagrammatic sectional elevation of a kiln.

Fig. 2 is a section taken similarly to Fig. 1 but on a larger scale and showing only a portion of the kiln shown in Fig. 1.

Fig. 3 is a transverse section taken on the line 3—3 of Fig. 2; and

Fig. 4 is a partial sectional plan taken on the line 4—4 of Fig. 3.

In the drawing A represents the horizontally elongated kiln chamber of a continuous tunnel kiln, which is shown as formed with benches A' at opposite sides of the pathway through the kiln for the goods carrying cars J. These cars enter the kiln at one end past a normally closed entrance door A², and leave it at the opposite end past a normally closed exit door A³. With the type of kiln illustrated, the porcelain ware carried through the kiln on the cars J, may be exposed to the kiln atmosphere, and is enclosed in saggars only when these form convenient means for giving the easily deformed ware its desired supports, and in such cases, the saggars need not be wadded to prevent free contact between the ware and the kiln atmosphere. On each of the benches A', for an intermediate portion of the length of the kiln chamber, is located a combustion chamber B. Each combustion chamber B as shown is connected at one end to a group of tubes C which run to the entrance end of the kiln where they connect with a header C'. The headers C' are connected, as by a tunnel C², to a suitable stack or exhaust fan, not shown, for creating the necessary draft to draw the products of combustion out of the combustion chambers and through the pipes C which form extensions of the combustion chambers. Between the opposite end of each combustion chamber and the exit end of the kiln chamber, a group of tubes D is located on the corresponding bench A'. These receive cold air as through the port D² at the exit end of the kiln, and deliver it much hotter into a corresponding header D' shown as connected to a duct D² which is connected in turn to the inlet of a fan E. The latter has its outlet connected, as shown, to a conduit EA through which a portion of the air passing through the fan is delivered to one or more burners in each combustion chamber adjacent the end thereof most remote from the

stack connection. Air passing the fan E in excess of the burner requirements may be passed to a drier or otherwise disposed of through a branch pipe EA¹⁰. Gas for combustion in the combustion chambers is supplied through suitable connections which may be branches of the gas conduits I hereinafter referred to. Each combustion chamber has its walls formed for the most part of tile sections b which extend transversely to the length of the combustion chamber and are formed with longitudinal open ended ventilating channels b'. The circulation channels in the tile sections b forming the bottom wall of the combustion chamber are open at their opposite ends to the kiln chamber proper. The channels b' in the side walls of the combustion chamber are connected at their lower ends to the channels b' in the bottom wall sections, and are connected at their upper ends to the channels b' in the tile sections forming the top wall of the combustion chamber. The tile sections forming the top wall of the combustion chamber are inclined, as shown, and the upper ends of the channels b' therein are open to the kiln chamber as may also, though not necessarily, be the case with the lower ends of these channels. With the combustion chamber construction described, a gravity circulation of the kiln atmosphere is produced by currents of the kiln atmosphere which enter the channels b' in the bottom walls of the combustion chambers, rise and are heated as they rise, through the channels b' in the side walls of the combustion chambers, and pass out into the kiln chamber structure at the top of the latter through the channels b' in the top wall portions of the combustion chambers. These currents descend through the goods pathway, and in descending impart a portion of their heat to the goods. In so far as above described the kiln illustrated is a typical Dressler kiln having combustion chambers of the general character disclosed in my prior Patent #1,170,428.

The kiln shown differs from an ordinary Dressler kiln in that an intermediate portion of the kiln chamber including the kiln zone of highest temperature, and an adjacent portion of the kiln at the entrance end side of the high temperature zone is divided into a series of compartments a, a, a, a', a', a', a², a², and a² by transverse partition walls which include special combustion chamber sections B', barriers B² mounted thereon, and transverse partition walls F depending from the roof of the kiln. These compartments communicate with one another through the central openings in the partition walls between them formed for the passage of the goods on the cars J. These openings are preferably restricted so as to give the smallest clearance possible consist-

ent with safety between the marginal edges of the partitions and the goods mounted on the car, the purpose being to restrict flow of the kiln atmosphere longitudinally of the 5 kiln. Advantageously also the roof of the kiln chamber is elevated somewhat in this portion of the kiln to give more volume to the spaces in the various compartments lying above the lower edges of the depending 10 partitions F. Each of the compartments a , a' , a^2 is provided with one or more outlets G. As shown there are two of these outlets for each compartment. These outlets each 15 comprise a stack rising from the top of the kiln and provided with its own regulating damper G'. Advantageously one or more outlets G may be provided for the kiln portions immediately adjacent the opposite ends of the series of compartments a , a' , and a^2 . 20 Associated with each of the compartments a , a' , and a^2 , are means for injecting a gaseous fuel into the compartment to modify and control the atmosphere therein. The preferred means shown for this purpose 25 comprises a series of inlet passages A⁵ formed through the side walls of the kiln chamber and parallel in direction and located at the same level as the channels b' in the bottom walls of the combustion chambers. 30 Nozzles H enter the outer ends of the passages A⁵ and the outer end of each nozzle H may receive gas from a gas supply pipe I through a corresponding valved connection I', may receive air from a compressed air supply pipe J through a corresponding valved connection J', and may receive steam from a steam supply pipe K through a corresponding valved connection K'. 35 As shown the pipe JK extends into the body of the nozzle H and is arranged so that the jet of air or steam discharged may act as an ejector jet for drawing gas from the corresponding connection I' and passing it with the desired velocity into the 40 kiln through the corresponding nozzle H. 45 In the preferred mode of operation contemplated, an oxidizing atmosphere is maintained in the compartments a and a^2 , and a reducing atmosphere is maintained in the compartments a' . The oxidizing atmospheres are maintained in the compartments a and a^2 by the injection of air into these kiln chambers through the corresponding nozzles H from the air supply pipe K. Preferably 50 this air is highly preheated and it may advantageously be supplied by the blower E with air heating means interposed between the blower and the nozzles H, though no air heating means of this character are shown. 55 The reducing atmosphere in the compartment a' may be maintained by supplying gas only to this compartment through the corresponding nozzles H, but some air may advantageously be mixed with the combustible gas supplied by the nozzles H. The air 60 thus supplied should be insufficient, however, for the complete combustion of the gas which would destroy its reducing character. The partial combustion of the gas imparts some heat to the kiln chamber compartments 70 a' which is sometimes desirable. In lieu of using air to prevent carbon deposits, steam, or a mixture of air and steam, may be supplied. The use of steam in conjunction with the combustible gas is desirable, in that it 75 effectually prevents carbon deposits in the channels b' and the resultant mixture of hydrocarbons, carbon monoxide and hydrogen resulting from the interaction of the steam and gas is highly reducing. The interaction between the steam and gas is endothermic and thus tends to lower the temperature in the compartments a' , but the amount of gas and steam which it is necessary to pass into the compartments a' in order to 80 maintain a strongly reducing atmosphere therein, is comparatively small and the heat loss from the endothermic reaction is relatively insignificant. It is to be noted more 85 over that with the comparatively small flow of air or gas or steam or mixtures thereof required for the maintenance of the desired atmospheres, the fluids flowing through the channels b' can be heated in their passage 90 through the latter, so that they issue from 95 the latter into the kiln chamber proper at the same general temperature as the kiln atmosphere into which they are discharged. 100 With the construction described it is readily possible to maintain an oxidizing atmosphere, a reducing atmosphere, or if need be a neutral atmosphere in any one of the compartments a , a' and a^2 . All that is required is to introduce the proper gaseous constituents into the compartment through the corresponding nozzles H. This ready control of the character of the atmosphere in the various compartments a , a' and a^2 makes it possible to shift the various oxidizing and reducing atmosphere zones longitudinally of 105 the kiln chamber, if and when this may be desirable to get the best operating results for any particular purpose and with any particular conditions in the kiln. The structure also permits the maintenance of other 110 arrangements of oxidizing and reducing atmosphere zones than the preferred contemplated arrangement specified above. By properly regulating the rate at which gaseous substances are admitted to the kiln chamber through the nozzles H and the suction through the various stack outlets G, it is possible to avoid appreciable flow longitudinally of the kiln from one compartment into another without creating pressure or flow conditions in the various compartments a , a' and a^2 preventing such circulation of the atmosphere therein, as is desirable to insure the desired uniformity of 115 heating. The special arrangement of bar- 120 125 130

riers or baffles employed to facilitate the maintenance of separate kiln atmospheres in adjacent compartments is not specifically claimed herein as it is so claimed in my co-pending application, Serial No. 382,001 filed concurrently herewith.

In the construction illustrated, see particularly Fig. 4, the spacing of the nozzles H is not the same as that of the channels 10 b' in the bottom wall of the combustion chamber. The purpose of this is to insure an appreciable flow through each of the channels b' adjacent the nozzles H notwithstanding the bodily movement of the combustion chambers B lengthwise on the supporting benches which occurs in practice on the thermal expansion and contraction of the apparatus, such relative movement of the combustion chambers and kiln walls prevents the maintenance of exact registry of the nozzles H and channels b'.

While in accordance with the provisions of the statutes I have illustrated and described the best construction for, and mode 25 of carrying out my invention now known to me, it will be apparent to those skilled in the art that changes may be made in the form of my invention as set forth in the appended claims without departing from the 30 spirit of the invention, and that some features of my invention may sometimes be used to advantage without a corresponding use of other features.

Having now described my invention, what 35 I claim as new and desire to secure by Letters Patent, is:

1. In a muffle heated continuous kiln the combination with a kiln chamber and the muffle heating means therefor, of means for 40 injecting fluid into a localized portion of the kiln chamber to make the atmosphere in that portion of the chamber either oxidizing or reducing as desired.

2. The method of glazing porcelain which 45 consists in passing the ware to be glazed through an elongated kiln chamber heated to

first gradually raise the ware to a predetermined temperature and then cool the ware as it passes through the chamber, and maintaining a reducing atmosphere in an intermediate portion of the kiln chamber and oxidizing atmospheres in portions of the kiln chamber at the opposite sides of said intermediate portion.

3. In a tunnel kiln the combination with 50 the kiln chamber, of a combustion chamber therein having a bottom wall formed with open ended horizontal channels extending transversely to the kiln chamber and having upper walls formed with channels extending 55 transversely to the combustion chamber and communicating at their lower ends with said bottom wall channel and open at their upper ends to the kiln chamber and nozzles mounted in the side wall of the kiln chamber for 60 discharging fluid into the interior of the kiln chamber through the bottom wall channels of the combustion chamber to thereby control the atmosphere in an adjacent portion of the kiln chamber.

4. In apparatus for treating porcelain the combination of a continuous tunnel kiln comprising an elongated kiln chamber, muffle heating means therefor, baffles within the kiln chamber providing a series of compartments therein connected by restricted openings normally obstructed to a substantial degree by the goods passing through said openings, means for injecting gaseous substances into the different compartments 70 and for withdrawing gaseous substances therefrom to thereby maintain a reducing atmosphere in one or more of said compartments and an oxidizing atmosphere in one or more adjacent compartments at each side 75 of the compartment or compartments in which the reducing atmosphere is maintained.

Signed at Cleveland, in the county of Cuyahoga and State of Ohio, this 12th day 80 of May, A. D., 1920.

CONRAD DRESSLER.
